[21] Appl. No.: 836,200

[57] CLAIM

The ornamental design for a hanging magazine rack or the like, as shown.

[22] Filed: Sep. 23, 1977

DESCRIPTION

[51] Int. Cl. ..... D6—04

FIG. 1 is a front perspective view of the hanging magazine rack or the like showing my new design, the rear being substantially plain and unornamented; and
FIG. 2 is a side elevational view thereof, the opposite side being substantially a mirror image of that shown.
